HUGO STAÜBLI, OF ZURICH, SWITZERLAND, ASSIGNOR TO GEBR. STAÜBLI & CO., OF HORGEN, SWITZERLAND.

APPARATUS FOR THE DRIVING OF A PATTERN MECHANISM OR SHED-FORMING MACHINE.

Application filed February 4, 1927, Serial No. 165,978, and in Switzerland May 18, 1923.

The present invention relates to apparatus for the driving of a pattern mechanism or shed forming machine according to the circumstances at will either by hand or mechanically. The possibility of this hand driving furnishes the weaver with the advantage of being able to rotate the shed forming or pattern mechanism, with the pattern-card cylinder, forwards or backwards at will when finding a broken weft or during return weaving, without also having to rotate the loom backwards or forwards at the same time.

One constructional example of the invention is illustrated in the accompanying drawing in front elevation in Figure 1 and in side elevation in Figure 2.

1 is the shaft which, by means of the cams 2, drives the lifting knives (not shown) of 20 the dobby, and which carries at one end a bevel wheel 4, with which there meshes a bevel wheel 5 mounted loose upon a shaft 6 driven by the upper loom shaft in the ratio of 1:1. Upon the other end of the 25 shaft 1 is fixedly mounted a spur wheel 7, with which a spur wheel 8, half as large in diameter, can mesh, which is mounted loose upon a stationary pivot 9 and is axially 30 slideable thereon. For the rotating and sliding of this wheel 8 upon the pivot 9, there serves a hand-crank 10, which is screwed or cast-on to the wheel hub. In order to limit the sliding, the pivot 9 contains two peripheral grooves 11, in which a pin 12 can 35 engage, which is carried by a presser lever 13 subject to spring pressure, supported upon the hub of the wheel. In a peripheral groove in the hub of the spur wheel 8 there is loosely mounted a rod 14, which is bent 40 at right angles at the bottom, directed parallel to the pivot 9 and guided in a bearing 30 and at the other end carries a link member 15. The latter is connected by a pin 16 with a bell-crank lever 17, the other arm 45 of which comprises a toothed sector 18, which meshes with a toothed segment of a double lever 19 which is rotatable about a pivot 20. The other arm of the double lever 19 embraces with a fork a pin 21, which 50 is located on one arm of a bell-crank lever 22, oscillating about a stationary pivot 23, 22, oscillating about a stationary pivot 23, being connected to a fork 24. The latter serves for the axial displacement of a clutch mem-

ber 25 which is mounted loose upon the shaft 6, and which carries two clutch claws 28 and 29, one at each end. By means of one of these claws 28, it can be coupled to the bevel wheel 5, which has a corresponding end claw, while the other, higher claw 29 of the member 25 serves the latter as a permanent guide on a claw member 26 mounted fast on the shaft 6, for the purpose of preventing the clutch member 25 from rotating upon the shaft 6. Between the two claw members 25 and 26 is inserted a compression spring 27 which tends to press the former against the bevel wheel 5, and keeps it in engagement with the latter during normal working.

The drawing shows the driving apparatus in the position in which the loom and the dobby, that is to say, the shafts 6 and 1, are coupled to one another by the wheels 5 and 4 and the claw clutch described above. The spur wheels 7 and 8 on the other hand are out of engagement with one another. If the dobby is to be disengaged from the loom when this latter is stopped the pin 12 is disengaged from the right-hand groove 11 in Figure 2 by pressing with the finger 70 upon the outer end of the pressure lever 13, and the wheel 8 is pulled by means of the hand-crank 10 against the wheel 7 and 75 meshes with the latter. This position is secured by the pin 12 snapping into the outer 80 groove 11. By the displacement of the wheel 8, the rod 14 has rotated the lever 17, and the latter, by means of its toothed segment 18 has rotated the lever 19. By this means the pin 21 located on the bell-crank lever 22 has been raised, and the lever 22 thereby rotated a short distance towards 85 the left out of the position shown in Fig. 1, and the claw member 25, through the medium of the fork 24, disengaged from the 90 bevel wheel 5. The dobby, due to the engagement of the wheels 7 and 8, can now be rotated at will in either direction by means of the hand-crank 10, the bevel wheel 5 remaining in engagement with the bevel wheel 4 and rotating loosely upon the shaft 6, and a turning movement of the dobby shaft 1 by one pick (one half revolution of this shaft) corresponding to one complete 95 revolution of the hand-crank 10.

When the dobby is to be coupled to the loom again the pin 12 is moved out of the left-hand groove 11, and the spur wheel 8

pushed back by means of the hand-crank 10. The latter wheel, however, can only be completely disengaged from the spur wheel 7 when the bevel wheel 5 mounted upon the shaft 6, assumes in relation to the clutch member 25 and therefore also to the shaft 6 exactly the same position as at the instant of unclutching, for only under these circumstances does the single claw of the member 25 facing the wheel 5 engage with the single claw of the wheel. In any other case it bears against the outer end face thereof and thereby prevents the complete backward rotation of the bell-crank lever 22 into its previous position. By this means the parts 19, 18, 17 and 14 are then also prevented from returning into their initial positions shown in the drawing. In this manner a guarantee is given that the dobby, although it can be released from the loom at any desired position, assumes exactly the same position in relation thereto at the instant when it is coupled with the loom again as it occupied at the instant of unclutching. If this position is not found after rotating the dobby by hand, it can be sought for by rotating the hand-crank 10 to and fro, as the wheels 7 and 8 could not be brought out of engagement. Hence during the entire duration of the working of the loom and the dobby there is no moment at which the shaft 1 is coupled through the bevel wheels 4 and 5 with the shaft 6, that is to say with the loom, and at the same time by the wheels 7 and 8 with the hand-lever. The possibility of the hand-crank 10 being driven, and the danger that would arise therefrom, is therefore absolutely precluded, this constituting a further advantage of the driving apparatus described. Furthermore it is advantageous that the dobby can be actuated by hand by means of the same hand-crank that serves for the opening and closing of the clutch.

In the above description it is assumed that the dobby is driven from the upper loom shaft. The drive may however be effected from the lower loom shaft. In this case the shaft 6 is driven in the ratio of 2:1 to the lower loom shaft, as the shaft 6 must revolve twice as fast as the lower loom shaft. Driving apparatus of the kind described may be inserted between the shaft 6 and a shaft driving the latter instead of between the shafts 1 and 6, in which case the shafts 1 and 6 may be in constant connection with one another. The clutch may be provided with two or more pairs of claws instead of with only one pair as shown and described.

60 What I claim is:—

1. Hand and power driving device for pattern mechanisms, comprising a power shaft, a shaft on the pattern mechanism, cams on this shaft for producing a reciprocating movement of pattern knives, a releasable

clutch adapted to transmit power from the first to the second of said shafts, a gearing through which said cams may be driven in either direction by hand, a hand operated device inserted between said clutch and gearing and adapted to simultaneously disconnect said shafts and connect said gearing. 70

2. Hand and power driving device for pattern mechanisms comprising a loom shaft and a shaft actuating the lifting knives of the pattern mechanism, a releasable clutch connecting these two shafts, a pair of mutually engageable and disengageable transmission elements which do not mesh with one another when the clutch is closed, a hand-crank which is not in driving connection with rotating elements during working of the loom, but connected with the releasable clutch member and with one of said transmission elements in such a manner as to bring this element 80 in engagement with the other when opening the clutch. 75

3. Hand and power driving device for pattern mechanisms as claimed in claim 2, comprising a claw-clutch having one set of claws located on a wheel mounted loose upon the driving shaft and permanently connected with the pattern mechanism, the claws on one side of the clutch being disposed with relation to that on the other side 90 in such a manner that the pattern mechanism admits of being released from the loom in any desired position, whereas it can only be recoupled in the same position relative to the said shaft. 95

4. Hand and power driving device for pattern mechanism comprising a driving shaft, a wheel rotatably mounted thereon and forming a clutch member, a shaft on the pattern mechanism, cams on said shaft for producing a reciprocating movement of pattern knives, two wheels fixedly mounted on said shaft, one of them permanently meshing with the wheel on the driving shaft, a hand operated driving wheel adapted to be brought in engagement with the second of said wheels on said shaft of the pattern mechanism, a clutch-member slidably mounted on the driving shaft to engage with the first-mentioned clutch-member, a mechanism connecting this second clutch-member with said hand-operated driving wheel in such a manner that when the hand-operated driving wheel is brought into engagement with the second of the said 110 wheels fixedly mounted upon the shaft of the pattern mechanism, the slidable clutch-member is released from the other clutch-member and thereby the driving connection 115 between said two shafts interrupted. 120

5. Hand and power driving device for pattern mechanisms comprising a driving shaft, a shaft on the pattern mechanism, cams on said shaft for producing a reciprocating movement of pattern knives, gearing 130

wheels on these shafts permanently meshing one with another, the gearing wheel on the driving shaft being loosely mounted thereon and provided with a clutching element, another clutching element axially slideable on the driving shaft but kept in constant radial relation thereto, said clutching elements being formed so as to enable their coupling only in the same relative radial position one 10 with another as they assumed in the instant of unclutching, a second gear wheel rigidly connected with the shaft of the pattern mechanism, a mechanism connected with the slideable clutching element, a hand-crank and a gear wheel loosely mounted on their pivot and connected with said mechanism, the last 15 mentioned gear wheel being adapted to be brought in engagement with the second gear wheel on the shaft of the pattern mechanism by the hand-crank by the same displacement thereof which by said mechanism, unclutches the clutching-elements.

6. Hand and power driving for pattern mechanisms including a driving shaft, a 25 dobbi shaft, cams on said shaft for producing a reciprocating movement of pattern knives, a bevel wheel rotatably mounted on the driving shaft and forming one of the 30 members of a claw-clutch, a second bevel wheel which permanently meshes with said first bevel wheel and is mounted on the dobbi shaft, a spur wheel fixed on this shaft, a second spur wheel axially slideable upon its 35 pivot, a hand-crank attached to this spur wheel, a rod gear connecting this second wheel with another member of the said clutch which member is axially slideable upon the driving shaft and rotating therewith, the breadth and axial travel of said second spur 40 wheel being so dimensioned on the one hand in relation to the position and breadth of the co-acting wheel and on the other hand in relation to the length of the path of the slideable clutch member that, when the latter assumes 45 the position which corresponds to the commencement of coupling, the two spur wheels are still in engagement with one another, so that the other clutch member can be brought into the coupling position in case 50 of need by rotating the hand-crank.

7. Hand and power driving device for pattern mechanisms, comprising a driving shaft, two clutch members mounted thereon, one 55 of these members rotatably mounted thereon and in permanent connection with a shaft of the pattern mechanism, cams on said shaft for producing a reciprocating movement of pattern knives, the other clutch-member being axially slideable on the driving 60 shaft, a claw member fixedly mounted upon this driving shaft and in permanent engagement with the slideable clutch-member to prevent it from rotation relatively to the driving shaft, a pressure spring interposed 65 between the said two members and tending

to bring the slideable clutch-member into engagement with that clutch-member which acts upon the dobbi-shaft, a fork engaging with the slideable clutch-member, a hand-crank loosely and slidably mounted on its 70 pivot, a bell-crank lever connected on one side with said fork and on the other side with the hand-crank in such a way that by axial displacement of the latter the slideable clutch member can be disengaged. 75

8. Hand and power driving device for pattern mechanisms, comprising a claw clutch having an intermediate slideable member and an external member on each side thereof one of these external members being 80 rotatably mounted on its shaft but prevented from sliding thereon, the other external member being fixed on the common shaft of the clutch, the intermediate clutch-member guided on and in permanent engagement with 85 the last mentioned external member, a bell-crank-lever, one arm of which is connected with said intermediate clutch member, a spur wheel slideable and rotatable on its 90 pivot, a rod and teeth gear connecting this spur wheel with the second arm of said bell-crank-lever, a shaft on the pattern mechanism, cams on said shaft for producing a reciprocating movement of pattern knives, a bevel wheel mounted on said shaft and meshing 95 with the first mentioned external clutch member, a spur wheel on the last mentioned shaft adapted to be engaged by the first mentioned spur wheel, means for limiting the axial displacement of this first spur wheel 100 between two extreme positions and for locking the spur wheel in these positions in such a manner that in one of these positions the two spur wheels mesh with one another and the said intermediate clutch-member is out 105 of engagement with the rotatably mounted external member, whilst, when the slideable spur wheel is in its other extreme position and out of engagement with the other spur wheel, the rotatable external clutch member 110 is in engagement with the intermediate clutch-member and thus coupled with its shaft.

9. Hand and power driving device for pattern mechanisms, as claimed in claim 8, 115 a rod connected to the hub of the hand lever and slideable spur wheel, a pair of toothed segments engaging with one another, a rod connecting one of these segments with said hub, a bell-crank lever connecting the other segment with the slideable member of the clutch. 120

10. Hand and power driving device for pattern mechanisms, comprising a hand-crank slidably and rotatably mounted on its pivot, a spur wheel rigidly attached to this hand-crank, a spur wheel fixed on a shaft of the pattern mechanism in the path of the axial displacement of the first spur wheel 125 and adapted to mesh therewith, cams on said 130

- shaft for producing a reciprocating movement of pattern knives, a claw-clutch on the power shaft with one claw on each of the coupling faces, one of the members of this clutch being in permanent engagement with the shaft of the pattern mechanism, the other clutch-member slidably mounted on its shaft, a rod and lever mechanism adapted to be operated by the hand-crank and connecting this slideable clutch-member with the spur wheel attached to the hand-crank, the axial dimension of the clutch-claws being in such relation to the axial displacement of the slideably mounted spur wheel, that this latter is out of engagement with the other spur wheel when the clutch is fully closed, but in engagement when the claws are in position just to come out of or into engagement one with another.
- 20 11. Hand and power device for pattern mechanisms, comprising a power shaft on the loom, a shaft on the pattern mechanism, cams on this shaft for producing a reciprocating movement of pattern knives, a releasable clutch inserted between said two shafts, a pair of mutually engageable and disengageable transmission wheels, not in engagement one with another when the clutch is closed, one thereof mounted on the cam supporting shaft, a hand crank rigidly connected with the other of said transmission wheels and adapted to bring it in and out of engagement with the other wheel by axial displacement, gearing members connecting said hand crank with a releasable part of said clutch in such a manner that the hand crank in disengaging the clutch by a sliding
- 25 30 35

movement on its shaft brings to engagement one of said transmission elements with the other.

12. Hand and power driving device for pattern mechanisms, comprising a power shaft on the loom, a dobby shaft, cams on this dobby shaft for producing a reciprocating movement of pattern knives, a bevel wheel gearing connecting said shafts one with another, one of these bevel wheels being loosely mounted on the power shaft, the other fixed on the dobby shaft, a claw-clutch on the power shaft adapted to couple the bevel wheel mounted thereon with the power shaft, a hand-crank slideably and rotatably mounted on its pivot, and stationary when the clutch is closed, a rod and gear device connecting this hand crank with a member of the claw clutch, this member being arranged to rotate with the power shaft but slideable thereon in axial direction so as to allow it to be coupled with and released from the bevel wheel loosely mounted on the power shaft, a spur wheel rigidly connected with the hand crank, another spur wheel fixed on the dobby shaft and adapted to be engaged by the first mentioned spur wheel by an axial displacement thereof, the arrangement being such that these two spur wheels are in engagement one with another at the moment where the claws on the clutch members are just in position to come into or out of engagement one with another.

In testimony whereof I have affixed my signature.

HUGO STÄUBLI.
